PIPE FITTING

Timothy J. Sullivan, Butte, Mont., assignor to
 Sullivan Valve and Engineering Company,
 Butte, Mont., a corporation of Montana

Application May 29, 1940, Serial No. 337,908

3 Claims.

(CL. 138—37)

This invention relates to pipe fittings, and more particularly to fittings for use in the so-called "one pipe" hot water heating systems.

It has been proposed to dispense with the cold water return pipe that is commonly employed in household heating systems by connecting the individual radiators as loop or branch circuits on a single pipe line that extends from the hot water outlet to the cold water return of the heating boiler. The prior constructions have not been entirely satisfactory in view of the difficulty in obtaining and maintaining a proper distribution of the heating medium to the several radiators of the system. The arrangements previously employed for diverting a part of the main stream of heating medium to the individual radiators were not adjustable and therefore failed to effect a proper distribution of the heating medium. Some improvement could be obtained by using different sizes of pipe, but this method of adjusting the frictional resistance to flow in different parts of the system does not permit of accurate design and the net result has been that the prior hot water heating systems of the one pipe design have usually failed to function efficiently.

An object of the present invention is to provide pipe fittings for use in hot water heating systems, the fittings including an adjustable valve that may be locked against accidental displacement. An object is to provide a pipe fitting of T form for use in a one pipe hot water heating system, the fitting including a valve that is pivotally mounted at a point spaced from the axis of the side opening of the fitting. A further object is to provide pipe fittings that include a pivotally mounted baffle valve having a stem that terminates in a non-circular head at the exterior of the fitting, and a locking cap having an opening for receiving the non-circular end of the stem, and means for securing the cap against rotation on the fitting.

These and other objects and advantages of the invention will be apparent from the following specification when taken with the accompanying drawing, in which:

Fig. 1 is a fragmentary schematic view of a heating system in which the novel fittings are used, and with a temperature measuring apparatus connected to one of the branch lines for determining the adjustment of the valved fitting;

Fig. 2 is a fragmentary side elevation of one radiator and the connections to the main circulating pipe of the system;

Fig. 3 is a central longitudinal section through a T fitting embodying the invention;

Fig. 4 is a transverse section of the same on line 4—4 of Fig. 2;

Fig. 5 is a fragmentary central section through another form of valved fitting and associated pipe connections;

Fig. 6 is a side elevation of another form of the invention; and

Fig. 7 is a central section through the same.

In Fig. 1 of the drawing, the reference numeral 1 identifies a hot water boiler having outlet and inlet connections 2, 3, respectively, that are connected by piping 4, 4' that forms a single path through which the water is circulated by a pump 5. A plurality of branch lines for the several radiators 6a, 6b, 6c are formed by connecting the radiator inlet and outlet pipes 7, 8, respectively, to T fittings that join the main piping 4 to the short pipe sections 4' that bypass the separate radiators. The T fittings 9 at the outlet side of each radiator are of conventional form but the T fittings 10 at the inlet side of radiators 6a and 6b are valved fittings that embody the present invention. As illustrated, both T fittings for the radiator 6c are of the usual design and a valve fitting 10' is included in the bypass section 4' to divert a desired quantity of the heating medium to the radiator 6c.

The quantity of water to be supplied to each radiator depends upon the size of the radiator and its location along the main path of water flow. The proper distribution of the heating medium to the several radiators may be readily determined by measuring the drop in temperature across the individual radiators. As shown in Fig. 1, a convenient form of temperature measuring apparatus includes thermocouples that are attached to the inlet and outlet pipes 7, 8 of a radiator by straps 12, and measuring instruments in a portable case 13. Readings are made at each radiator, with all radiator valves fully open and the adjustable fittings set for a minimum diversion of water from the circulating line 4, 4' to the radiators. The adjustable fittings are then set to divert more water to those radiators that showed the larger temperature drops, and the temperature drops across the radiators are again measured. These steps are repeated until the fittings are so adjusted that the same temperature drop obtains across all of the radiators. Each radiator then develops its calculated heat output and carries its proper share of the total heating load.

As shown in Figs. 2—4, each valved fitting 10 in-

cludes a disk or deflecting baffle 14, of appreciably smaller diameter than the bore of the fitting, on the squared section 15 of a stem that is pivotally supported within the head section of the T fitting, the stem being normal to the axis of the branch section and displaced from that axis by at least the radius of the bore through the branch section. The central part of the disk 14 is preferably slotted and reversely bent to provide strips 16 that fit about and are brazed to the shaft 15. The inner end 17 and shouldered intermediate portion 18 of the stem are of circular cross-section and provide the pivotal mounting of the stem on the fitting. The cylindrical inner end 17 is journaled in a recess in the inner wall of the fitting and the outer end of the stem is journaled in and extends through the internally threaded and counterbored boss 19 of the fitting. The packing 20 is compressed upon the shouldered portion 18 by the gland nut 21 to anchor the stem against axial displacement and to seal the bore of the boss 19. The outer end 22 of the stem is given a non-circular cross-section by cutting away opposite sides to leave an elongated central zone of the original cylindrical stem section, and the disk 14 is assembled on the stem with the plane of the disk parallel to the flattened section of the stem. A cap 23 is telescoped over the cylindrical boss 19 of the fitting and has an elongated opening in its outer wall to receive the flattened end 22 of the stem, the outer surface of the cap being hexagonal to receive a wrench for adjusting the stem. A set screw 24 extends through the cap to lock it, and thereby the baffle disk 14, against displacement after the baffle is set to divert the desired quantity of water to the radiator.

A smooth non-turbulent flow of water is obtained when the baffle is located beyond the branch connection, see Fig. 3, and an arrow 25 or other symbol is cast or cut into the fitting to indicate the proper direction of flow through the fitting. The flattened end 22 of the stem is indicative of the setting of the baffle disk 14, and thus serves to prevent adjustment of the disk into a position that would cause a turbulent flow or a high resistance to flow through the fitting.

It is preferable to locate the baffle disk in a T fitting for new installations as the distribution of water to the several radiators is then obtained with a minimum of resistance to flow. The distribution of the heating medium to the radiators of existing one pipe systems can be improved through the use of coupling members 10', as shown in Fig. 5, that are provided with a baffle disk 14' on an adjustable stem 15'. A valved fitting of this type can be introduced into existing piping by cutting the bypass section 4' and inserting the fitting in the usual manner through the use of a compression coupling that may be a separate unit or a part of the valved fitting.

As shown in Figs. 6 and 7, the invention may be embodied in copper fittings 10a of the type that are to be sweated or soldered to copper pipe. The

internal construction is substantially as shown and described in connection with the threaded fittings of Figs. 1-5. The cap 23a and its set screw 24a are similar to the corresponding parts of the Fig. 4 construction, and an arrow 25a is cast or marked upon the exterior of the fitting to indicate the proper direction of flow through the fitting.

The valved fittings may be employed with any type of radiator but are particularly useful in systems that employ a pump for circulating the hot water through radiators of the tubular core and fin type. The resistance to flow through such radiators is relatively high and it is therefore desirable to distribute the correct amount of water to each radiator without unduly increasing the total flow resistance. The valve T fittings divert the desired quantity of water to the radiators with a minimum of disturbance that would increase the flow resistance.

I claim:

1. A T-fitting for use in a one pipe hot water heating system, said fitting comprising a head portion having aligned sections for connecting the fitting into the main pipe line of the heating system and a branch portion terminating in means for connecting to the inlet pipe to a radiator, a deflecting disk within the head portion of said fitting and having a diameter substantially less than the bore of the head portion, a shaft carrying said deflecting disk, said shaft having an inner end and a shouldered intermediate portion of circular cross-section, and means pivotally mounting said shaft on the head portion of the fitting with the axis of the shaft normal to the axis of the branch portion and displaced therefrom by substantially the radius of the bore of the branch portion; said mounting means comprising a recess in the inner wall of the fitting to receive the inner end of said shaft, a counterbored and internally threaded boss on said fitting constituting a journal for said shouldered intermediate portion of the shaft, and a gland packing compressed into said boss to anchor said shaft against axial displacement.

2. A T-fitting as claimed in claim 1, wherein said shaft extends through said boss and has a non-circular outer end, in combination with a locking cap fitting over said boss and mechanically interlocking with the non-circular outer end of the shaft, and means to secure said cap against displacement with respect to said boss.

3. A T-fitting as claimed in claim 1, wherein said shaft extends through said boss and terminates in a flattened outer end, the major transverse axis of the outer end of the shaft being parallel to the plane of the deflecting disk, in combination with a locking cap fitted upon said boss and having an end wall with an elongated opening within which the outer end of the shaft is seated, and a set-screw threaded into said cap for locking engagement with said boss.

TIMOTHY J. SULLIVAN.
